UNITED STATES PATENT OFFICE.

SAMUEL EDELSOHN, OF NEW YORK, N. Y.

DESIGN FOR A DOORLOCK.

Application filed February 19, 1923. Serial No. 5,202. Term of patent 14 years.

To all whom it may concern:

Be it known that I, SAMUEL EDELSOHN, a citizen of the United States, residing in the borough of Manhattan, in the city and State of New York, have invented a new, original, and ornamental Design for Doorlocks, of which the following is a specification, reference being had to the accompanying drawing, forming part hereof.

Figure 1 is an elevation of the lock and the keeper or frame plate,

Figure 2 is a plan view thereof.

The lock and keeper are sold as a unitary device.

I claim:

The ornamental design for a doorlock, as shown.

SAMUEL EDELSOHN.
